CHARGING ELECTRIC FURNACE

Lee Frank Weitzenkorn, Dundalk, Md., assignor,
by mesne assignments, to Armco Steel Corporation,
a corporation of Ohio

Application July 23, 1945, Serial No. 606,555

1 Claim. (Cl. 214—152)

1

My invention relates to electric arc furnace practice, and more particularly concerns a novel mode of introducing therein the chrome ore or similar ore which is to be subsequently processed and reduced.

An object of my invention is to provide a new and novel method of introducing chrome ore into an electric arc furnace in such manner that the ore is distributed gently and with a natural angle of repose about the banks of the furnace.

Another object is to provide a method of the general type of the foregoing, wherein chrome or other ore is supplied to the furnace in uniform and even supply, and with controlled and uniform feed in simple, reliable and certain manner whereby ore conditioned for rapid reaction in the furnace can be charged therein with regulated and controlled volume and the ore placed at any desired point. Thus, illustratively the ore can be quickly and readily supplied to those points within the furnace where the layer of ore momentarily appears to be thin.

Still another object is to provide a method of the general type described wherein all tendency of the ore to clog in the delivery process is effectively eliminated, the ore falling gently on the banks of the furnace, and all danger is effectively eliminated of delivery at too great a velocity or with too great a force so as to dislodge the deposited ore. Surging and jamming no longer constitute a problem, and the rate of feed from the hopper and the velocity with which the ore is deposited both are subject to full and sensitive control, hand-shoveling being effectively avoided.

Other objects and advantages will in part be obvious and in part pointed out hereinafter during the course of the following description.

My invention accordingly resides in the several procedural and manipulative steps and in the various combinations of each of the same with one or more of the others, the scope of the application of all of which is more fully set forth in the claim at the end of this specification.

In the drawings, wherein I disclose one embodiment of my invention which I prefer at present of equipment facilitating the practice of my new invention, Figs. 1 and 2 respectively illustrate apparatus for practicing my invention, and the laying of ore onto the banks of an electric arc furnace in accordance therewith.

As conducive to a more thorough and complete understanding of my new invention, it may be noted that in the past three or four decades, the use of the electric arc furnace has come into

greater and greater acceptance in the processing of irons, steels and other "heavy" metals. Despite the substantial operational expense of these furnaces as compared with the coke-fired open-hearth furnace and the Bessemer, and despite the comparatively small capacity of electric units, the high temperatures required for the melting of high alloy steels and other specialized alloy metals have dictated the use of such equipment in producing such steels. The widespread expansion of this type of metal processing has resulted in the rapid refinement and development of the furnace equipment itself. At the present time, therefore, the electric furnace has reached a high state of development. Contamination of the heat undergoing processing is reduced to a minimum. Products of high purity and accurate analysis are obtained, and operational times are reduced to a minimum, while unit capacity has been increased. Operating in batteries of two, four, six or more furnaces substantial operational efficiencies are achieved, limited almost entirely by unit power costs.

Holding step with the development of the electric arc furnace if not exceeding it, is the evolution of what are known as stainless steels, by which of course is meant the now well-known chromium alloy steels which are so widely used in all walks of industrial, commercial and residential use. The utilization of such metals of varying percentage composition runs the entire gamut from armor plate to lamp reflectors, ornamental bric-a-brac, cooking utensils and the like. The evolution of such steels and the widening demand therefor, both as to quantity and as to extent of utilization, has in itself spurred the development of the electric furnace.

This is because a high degree of purity is required with close adherence to the percentage composition sought. For these reasons, the use of the basic or acid open hearth methods of processing as heretofore known have proved entirely unsatisfactory in the production of stainless steel. By processes of evolution, together with selective elimination over a period of years the production of chromium metals has been almost entirely limited to electric furnace equipment.

Now, in electric furnace practice, it is customary to hand-charge the ore about the walls or banks of the furnace. This is slow and time-consuming, and requires a large labor gang. In point of fact, this "patching," as is called the distribution of chrome ore along the banks of

the furnace, comprises a most expensive manipulation, due primarily to the labor costs involved, but also to the time consumed in processing a particular batch or charge into the furnace.

Although in many instances the electric furnace is employed essentially as a finishing furnace for processing stainless steels already partially treated in either the open hearth or acid process, the operators have always been most active in undertaking to reduce the costs of operation and to bring them more nearly in line with the operational costs of the methods and processes heretofore in use. In this way they argued, as has already been pointed out, that increased utilization could be achieved of the electric furnace products such as chrome steels and the like. In an attempt to reduce the labor costs, therefore, and to step up the operational time requirements, it has been suggested to blow the chrome ore into the furnace. For one reason or another, however, these expedients failed to give entirely satisfactory results. To illustrate, in many instances regulation of the flow of the material was impractical. In the usual design of a pneumatic blower, comprising essentially an open hopper containing the ore and a siphon or venturi which conveyed the ore to the air holes and discharge pipes, it was found that the ore tended to clog either in the siphon or in the bottom portion of the hopper. At the best, it flowed in a very irregular pulsating stream. In one instance, the ore would surge forth in quantity, the air mixture being quite enriched therewith. The next moment the unit quantity delivered would be much decreased, and the air mixture would be practically devoid of ore. Moreover, the rate of delivery was likewise found to be pulsating, so that the ore could not be properly banked around the walls of the furnace.

An important object of my invention, therefore, is to avoid in substantial measure the many disadvantages and defects of the art as it existed prior to my invention and at the same time to provide a method rapid, time-saving, certain and precise in nature, for uniformly discharging and depositing chrome or similar pre-dried ore at the desired point of application with a gentle arc whereby the ore can be deposited in its natural angle of repose, in which all pulsation and irregularity in feed is avoided along with all tendency of clogging and tendency for the deposited ore to be blown away from its point of deposition, and as well, to supply the ore at controlled unit volume and at controlled unit velocity.

Basically, my invention comprises discharging a stream of hot pre-dried chrome or similar ore from the end of a flexible pipe in and about the walls or banks of an electric arc furnace. A pneumatic blower is employed successfully operable with substantially any type of granular or powdery ore. Regulation of the discharge velocity and control of the quantity and direction of the ore stream makes it entirely feasible to place the ore in any desired spot within the furnace, and in any desired quantity, simply by turning the flexible hose in that direction.

In practice my invention may be stated as comprising placing the ore to be discharged in a tightly closed container, and equalizing the air pressure both above and below the ore. This prevents improper surging in the discharge line and moreover, prevents clogging and jamming of the ore which feeds into the discharge pipe. Inasmuch as the pressure of both the top and

bottom of the chrome ore in the hopper is equalized, the ore flows by simple gravity feed. A suitable valve regulates the flow from the hopper. An air line serves to pick up the chrome ore passing through a Venturi column, whereby the pressure component of the air is sacrificed in order to increase the velocity component thereof. The stream of air, carrying entrained ore with proper density of ore and proper velocity of discharge, is passed through a flexible metal hose whence it is spread into the furnace in desired manner.

It is important in the patching operation according to electric arc furnace practice that the chrome ore fall in a gentle arc so that the stream of the ore may be placed at any point therein and at any quantity on the banks of the furnace, allowing the ore to pile against its banks in its natural angle of repose. Any appreciable variation of the angle of deposition from the natural angle of repose of the material would result in the deposited material breaking away from its anchorage and collapsing into the bed of the furnace. The flexible metal hose can be so manipulated through the door of the furnace and the rate of feed and velocity components so selected that these objectives can be accomplished in highly satisfactory and accurately predetermined manner.

To illustrate this more effectively, reference may now be had to the specific structure which I illustratively employ for the practice of my invention and which is shown in Fig. 1 of the drawings. Therein a hopper 10 for the chrome or similar powdery or granular ore is provided. This is generally cylindrical in form with an inverted truncated conical bottom 11. A removable pressure cover 12 is hinged at 13 to the top of tank 10, latch 14 being provided on the top periphery of the tank diametrically opposed to hinge 13, for securing the pressure cover 12 in place. At its lower part the inverted truncated bottom 11 terminates in a delivery column 15, which opens into a channel 16. This channel 16 is connected at its left end in the figure to a variable source of air not shown, a main air control valve 17 being provided for further manipulative variation in the incoming air.

It has already been stated that it is an object of my invention along with the other component elements thereof resulting in the final new achievement, that the flow through the hopper 10 be entirely by gravity. In this manner, the surges which have heretofore resulted from air feed of the chrome or other ore are effectively avoided. It is for this reason, as well as to reduce in large measure the effect of the external atmosphere, that the removable pressure cover 12 is provided. This is substantially sealing in nature. The desired objective of gravity pressure within tank 10 is accomplished by equalizing the air pressure on both the top and bottom of the ore so that the latter falls of its own weight. This is accomplished by by-passing part of the air from conduit 16 before it reaches throat 15 up to the upper air-space 18 of the tank 10, above the level of the chrome ore.

To this end a conduit 19 is provided leading from main conduit 16 to the space 18. An air pressure gauge 20 is provided for accurate determination of the pressure conditions maintaining in this line, while an air control valve 21 is provided in conduit 19 for accurate control and regulation of these pressure conditions. When

the pressure conditions are equalized in line 16 and upper space 18 of tank 10, the feed of the chrome ore is entirely under the influence of gravity.

The rate of feed through throat 15 is limited by a flow regulator 22 provided in conduit 16 and extending up into throat 15 of tank 10. While this regulator may be of any conventional type, I here find it desirable to provide a conical valve member 23 which extends up into the throat 15 and for which threaded regulation is provided by means of shaft 24. By backing the conical portion 23 partly out of throat 15 and into the air column conduit 16, variation in the rate of flow can be accurately controlled. On the other hand, regulation of the main air valve 17 will in turn accurately control the velocity with which the gravity-fed chrome ore is forced to the right in the conduit 16 beyond throat 15.

To increase effectively the velocity component of the air passing through conduit 16, together with the entrained and entrapped chrome ore, at the sacrifice of the pressure component thereof, I provide a Venturi column 25 in conduit 16, to the right of the throat 15. A flexible metal hose 26 of strength sufficient to withstand the rigors of extensive and heavy use, and constructed of materials capable of withstanding at least moderately prolonged exposure to the substantially elevated temperature within the furnace, is made fast to the free end of the venturi 25 at the right in the single figure. This in turn terminates in a discharge nozzle 27, somewhat in the form of an elongated wand and at the free end thereof terminating in a discharge orifice 28.

The operator stands at the door of the furnace and inserts the wand 27 thereinto, see Fig. 2 of the drawing, and, aided by suitable protective clothing, goggles and the like, is able without appreciable discomfort to manipulate the wand so as to feed the chrome ore in a gentle arc along the banks of the furnace, depositing the same thereon in its natural angle of repose. He is readily able to place the stream of ore at any point within the furnace. Simply by retaining the wand in a particular point for a sufficient length of time he can build up or patch the furnace at that point to the desired thickness of chrome ore layer. By having a helper manipulating the flow regulator 22, he can accurately control the unit quantity of chrome ore delivered from tank 10, while by manipulation of valve 17 the velocity of the stream can be readily controlled. Required gentle delivery consistent with the characteristics of the particular ore being charged is thus ensured. The helper can also make frequent observations of the pressure in the upper portion 18 of tank 10 by reading pressure gauge 20 and can make such compensatory adjustments as may be required through manipulation of control valve 21 in bypass 19. Removable pressure cover 12 may be released at latch 14 and swung back at any desired time to replenish the supply of chrome or other ore. Upon re-

placement of cover 12 to its rest position, the equilibrium pressure conditions are restored.

In the foregoing manner, the chrome ore is introduced into the furnace in accurately controlled quantity, and in accurately controlled positioning, so that at all times the furnace is enabled to function at maximum efficiency. Full utilization is made at all times of the expensive energy input which is required. The batch through the even distribution thus achieved, is subjected uniformly to the developed heat and the operating time is reduced to a minimum. Ore flow is uniform and non-pulsating. All these and many other highly desirable and practical results attend upon the practice of my new invention.

Many colorable variations and adaptations of my invention will readily occur to those skilled in the art once the broad aspects thereof are disclosed. Moreover, the skilled technicians in this field will readily evolve many modifications of the technique herein set forth. Accordingly, I intend that the foregoing disclosure be treated merely as illustrative, and not by way of limitation.

I claim:

The method of laying chrome ore onto and about the banks of an electric arc furnace in patching the same, comprising gravity feeding a constant controlled unit quantity of granular hot pre-dried chrome ore into a separately regulatable air stream by applying the pressure of said air stream back of the supply of hot pre-dried ore as well as at the point of the ore entering said stream, restricting the flow of said air stream with entrained hot pre-dried ore to limit the area of the stream and uniformly increase the velocity of the ore, passing the air column with hot pre-dried ore addition into the furnace as a controllable stream, and discharging the stream of air with entrained hot pre-dried ore at various desired points and in desired quantities about the banks of the furnace.
